UNITED STATES PATENT OFFICE.

CARL F. DAHLBERG, OF NEW ORLEANS, LOUISIANA.

PLASTER BOARD.

Application filed October 28, 1922. Serial No. 597,677.

To all whom it may concern:

Be it known that I, CARL F. DAHLBERG, a citizen of the United States, residing at New Orleans, in the parish of Orleans and State of Louisiana, have invented certain new and useful Improvements in Plaster Boards; and I do hereby declare the following to be a full, clear, and exact description of the invention, such as will enable others skilled in the art to which it appertains to make and use the same.

This invention relates to plaster boards and has for its object to provide a device of this nature which will be simple in construction, comparatively inexpensive to manufacture, and more efficient in use than those heretofore proposed.

With these and other objects in view the invention consists in the novel details of construction and combinations of parts more fully hereinafter disclosed and particularly pointed out in the claims.

Referring to the accompanying drawings forming a part of this specification in which like numerals designate like parts in all the views:

Figure 1 is a plan view of one form of plaster board made in accordance with this invention;

Figure 2 is a plan view of another form of the invention;

Figure 3 is a sectional view taken on the line 3—3 of Figure 1, looking in the direction of the arrows;

Figure 4 is a sectional view of the board shown in Figure 2, when attached to the wall of a building;

Figure 5 is a sectional view of a board of the kind shown in Figures 1 and 3, with its two members held together by a plastic coating material;

Figure 6 is an enlarged sectional view of a board similar to that shown in Figure 5, with its members individually coated with a plastic material and held by a like material; and

Figure 7 is a perspective view of a completed board section adapted to overlap with one or more similar sections.

In order that the precise invention may be the more clearly understood it is said:— It is now well known that a fibrous heat insulating wall board known on the market as "Celotex" is usually produced in lengths of say six to ten feet and in widths of say four feet although any other dimen-

sions may be had if desired. This board constitutes a material of great utility in the making of inside as well as outside walls of buildings, and for many other purposes. When used as the walls of buildings it may be attached directly to the studding or to the sheathing and plaster or stucco applied thereto. But, when stucco is used and sometimes when plaster is used, it is desirable to provide a better means for bonding or securing the same to the board than is afforded by the continuous fibrous outer surfaces of the same; and in most cases it is desirable to prevent moisture from entering and collecting in the porous interiors of these boards.

These said "Celotex" boards are made from partially cooked fibres of bagasse from which the incrusting material has been removed and these fibres are found in the finished board, to be of a threadlike form of varying lengths and sizes. They also retain their individuality in so far as flexibility and strength are concerned. They are thus in marked contrast to the fibres found in other boards made from bagasse wherein the chemical treatment has more or less broken down the individual fibres into a colloid like mass.

These said "Celotex" thread like fibres in the finished board are interlaced with each other into a coherent mass which is permeated with interstices serving to entrain abnormal quantities of air. These interstices give to the board as a whole an abnormal heat insulating capacity, and render the same peculiarly valuable for the covering and lining of the walls of buildings in both hot and cold climates and for other purposes. It therefore becomes an important matter to bond stucco and plaster to these boards in an inexpensive and satisfactory manner.

This problem has been solved by this invention as will now be disclosed.

Referring to Figures 1 and 3 of the drawings, 1 indicates a fibrous "Celotex" board, made from partially cooked bagasse fibres and having the oblong perforations 2 passing entirely therethrough. The board 1 or 11 may be made of any desired or suitable dimensions as to length, breadth and thickness, but the latter will usually only vary between say one fourth of an inch and one inch. In these uses where a high degree of heat insulation is desired, the said board

1 or 11 is secured by any suitable means to a second fibrous bagasse or other board 3. The securing means in Figures 1 and 3 are illustrated as staples 4, while in Figures 5 and 6 the securing means is a plastic substance 5. It is preferred to make the board 1 somewhat thinner than the board 3, as is indicated in Figures 3, 5 and 6, and it is also preferred to make the perforations 2 tapered or undercut as is illustrated at 6 in order to better hold the plaster, stucco or other plastic material 7 that may be applied thereto.

In the preferred form of the invention 15 the member 1 is suitably coated with a plastic waterproofing material 8, such as pitch asphaltum or the like, the member 3 is likewise coated with the same material, and the two members 1 and 3 are stuck or bound together by said material as illustrated in Figure 3. Or, after said members 1 and 3 are thus coated, an additional coating 5 may be applied as illustrated in Figure 6. In either case the moisture from the wet plaster or stucco is prevented from entering the board.

In the form of the invention shown in Figure 2, only the single bagasse fibre board 11 is employed, which in this instance is provided with round holes 10 extending entirely through the board and which are bevelled or undercut as at 6 as shown. This single board 11 may be made of any desired dimensions and nailed directly to the sheathing 12 or other supporting base as indicated at 13, Fig. 2, or it may be otherwise attached.

In Figure 7, the base supports 14 are shown at 15, as extending beyond the perforated members 1, and as forming squares or sections while the perforated members extend beyond two edges of said sections to overlie the spaces 15 on the adjacent bases 14, to the end that a substantially continuous perforated plaster or stucco holding surface is provided.

In all the forms it will be seen there is employed a yielding fibrous bagasse material in the making of the perforated boards 1 and 11, so that as the stucco, plaster or other material 7, sets, the boards 11 and 1 will yield sufficiently to avoid the cracking of the applied plastic material, which is now experienced when unyielding lath boards of wood are used. In addition to this, even when the building settles to a slight extent it is found the yielding nature of this bagasse material functions to lessen the severity of the cracking of the stucco, and plaster, and in many cases it eliminates said cracking entirely.

The perforations 2 and 10 are conveniently made by rotary punching machines and the coatings 8 are also conveniently applied by suitable machines. In the punching operation the material is compressed as is indicated at 20, which strengthens the corners 21 of the perforations, and thus enables one to use a cheaper grade of "Celotex" material for the boards 1 than for the 70 boards 3.

It is obvious that those skilled in the art may vary the details of construction without departing from the spirit of the invention, and therefore, I do not wish to be limited to the foregoing disclosure except as may be required by the claims.

What is claimed is:—

1. A heat insulating plaster board comprising a body portion of compressible fibrous bagasse material provided with undercut perforations, the acute edges of said perforations being formed of more greatly compressed fibers than the fibers of said body portion, and a supporting base of compressible fibrous bagasse material to which said body portion is attached, said body portion and said supporting base being coated with a waterproofing material.

2. A heat insulating plaster board comprising a body member composed of compressible fibrous bagasse material provided with undercut perforations, the acute edges of said perforations being formed of more greatly compressed fibers than the fibers throughout the rest of said body member, and a supporting base member of compressible fibrous bagasse material attached to said body member so that said base member extends beyond an edge of said body member, said body member and said base member being each coated with a plastic pitchlike waterproofing material.

3. A heat insulating plaster board comprising a body member, composed of partially cooked compressible bagasse fibers, provided with undercut perforations, the acute edges of said perforations being formed of more greatly compressed fibers than the fibers throughout the rest of said body member, and a supporting base member likewise composed of partially cooked compressible bagasse fibers, attached to said body member so that said base member extends beyond an edge of said body member, said body member and said base member being each coated with a plastic pitchlike waterproofing material.

In testimony whereof I affix my signature.

CARL F. DAHLBERG.
